MARKING DEVICE

Filed April 14, 1930

UNITED STATES PATENT OFFICE

HERBERT E. EDWARDS, OF BROOKLINE, MASSACHUSETTS, ASSIGNOR TO T. J. EDWARDS INCORPORATED, OF BOSTON, MASSACHUSETTS, A CORPORATION OF MASSACHUSETTS

MARKING DEVICE

Application filed April 14, 1930. Serial No. 444,069.

The present invention relates to marking devices and more particularly to marking devices for marking a line for use as a guide in a subsequent operation such, for instance, as the application of overlays to shoe upper blanks.

In the marking device illustrated and described in my Patent No. 1,753,884, April 8, 1930, the bed thereof carries a stationary pattern for supporting an upper blank and a stationary ink pad for supplying ink to a marking pattern which is moved from a position where it engages the ink pad to a position where it engages the supported blank.

15 The mark made by the marking pattern on the supported blank should be sharply defined to provide the operative, who performs the subsequent operation, with a legible guide line. At the same time the sharply defined line should be delicate to insure its registry with the overlapped overlay or other assembled part.

To produce this delicate guide line the marking pattern is provided with a depending flange terminating on its bottom in a narrow face forming a marking edge. This edge, while sharp, is not sharp enough to cut into and injure the upper blank which is engaged but once thereby. The sharp edge, 25 however, engages the ink pad repeatedly and soon wears an indentation into the felted or fibrous material of which the ink pad is composed. This indentation forms a trough in which the ink collects when the pad is replenished with liquid ink with the result that not only the narrow face forming the marking edge, but the adjacent sides of the depending flange, pick up ink each time the marking pattern is returned to the ink pad.

40 The excess ink on the sides of the flange spatters or spreads onto the upper blank and remains there throughout the upper fitting and shoe making operations. The disfiguring spots or streaks of ink are not removed until the shoes are finished, and therefore, considerable care and labor must be expended in eradicating the ink. Sometimes, particularly in the case of shoes having ornate fabric uppers, attempts to eradicate the ink therefrom result in botcheries. Even if the excess ink

does not actually spatter upon or spread onto the upper blank during the marking operation, it dries on the sides of the flange gradually thickening it, thus widening the marking face on the bottom thereof with the result that on the upper blank a wide ragged line is marked which causes irregularities in the subsequent operation. As the overlapped part, an appliqué or an assembled upper blank, cannot hide completely the wide ragged guide line, the exposed portions thereof must be removed before the shoes can be sold.

45 As the marking patterns used with my marking device are interchangeable, and as no two patterns are alike, the result is that in the continued use of the felted or fibrous ink pad it becomes sulcated by the cutting action of the various sharp edges on the marking patterns. This condition promotes the transfer for excess ink to the upper blank either directly, or through the thickening of the marking edge face throughout its length, or along portions thereof embraced by the ink containing grooves of the sulcated ink pad.

50 The principal object of the present invention is to provide a marking device of the class described with a marking substance pad immune from sulcation.

To the accomplishment of this object a feature of the present invention contemplates the provision in a marking device of the class described, of a sponge rubber marking substance pad having a consolidated tegument.

55 While a sponge rubber pad having a consolidated tegument is capable of being engaged repeatedly by the sharp edge faces of the marking patterns without being sulcated, the consolidated tegument is impervious to the marking substance and therefore the capacity of such a pad as a source of marking substance is limited.

60 Accordingly, another feature of the present invention contemplates the provision in a marking device of the class described having a pad and a marking pattern, of means for supplying the pad with marking substance during each cycle of operations of the marking pattern.

Broadly considered the means for supplying the pad with marking substance may take any convenient form found desirable or expedient. It is preferred, however, to employ 5 a vulcanized sponge rubber roll having its tegument removed to render it pervious to the marking substance. The roll is transferred from a source of marking substance supply over the pad and back to the source 10 of supply during each cycle of operations of the marking pattern. Preferably, the roll is transferred under pressure to insure its leaving a thin coating of substance material upon the consolidated tegument of the pad. 15 Other features of the present invention consist in certain devices, combinations and arrangements of parts hereinafter described and then pointed out broadly and in detail in the appended claims which possess advantages 20 readily apparent to those skilled in the art.

The various features of the present invention will be readily understood from an inspection of the accompanying drawings illustrating 25 the best form of the invention at present known to the inventor, in which,

Figure 1 is a view in plan of the marking device;

Fig. 2 is a view in sectional elevation on 30 the line 2—2, Fig. 1;

Fig. 3 is a detail view in plan of one of the marking patterns, and

Fig. 4 is a detail view in sectional elevation on the line 4—4, Fig. 3.

In the illustrated embodiment of the invention the work to be marked, herein shown as a vamp 3 (Fig. 1), is mounted flatwise upon a gage 4 with the peripheral edge of the throat 5 of the vamp engaged with a wall 40 comprising a plurality of small cylindrical blocks 6. Each of the blocks 6 is secured to one end of the shank of a rivet 7 (Fig. 2) which passes through the gate 4, the rivet being headed on the bottom thereof. The 45 gage 4 is supported by a rectangular plate 8 (Fig. 2) secured to the horizontal flanges 9 of a bed 10 adapted to be supported from a work bench or table (not shown). The gage 4 is interchangeable with other gages 50 and therefore is removably connected to the plate 8 by means of vertical dowels 11, secured to the plate, which receives eyelets 12 set into the gage 4 adjacent its rear corners. The gage 4 may be clamped in engagement 55 with the plate 8 by inturned jaws 13 and 14 arranged on opposite sides of the gage. The shank of each of the jaws 13 and 14 is slotted (Fig. 2) to embrace the shank of a screw 15 which is threaded into the base 10 and provided both with a fingerhold 16 and a wrench 60 engaging nut 17.

In the illustrated embodiment of the invention the vamp 3 is marked with a pair of lines 300 for use as a guide in a subsequent 65 operation. Each line 300 is formed by a

narrow face 18 (Fig. 3) formed on the bottom of a vertical flange 19 supported from a block 20. The block 20 is interchangeable with other blocks carrying marking faces 18 having different configurations and is therefore detachably connected to a cross-head 21 and to an operating handle 22, substantially in the manner illustrated and described in the patent to Woodworth numbered 1,639,360, dated August 16, 1927.

At its front end the cross-head 21 is journaled on bearings carried, respectively, by the upper ends of arms 23 and 24 projecting from the opposite ends of a horizontal rock-shaft 25 journaled in the bed 10. At its rear end the cross-head 21 is journaled on bearings carried, respectively, by the upper ends of arms 26 and 27 projecting from the opposite ends of a horizontal rock-shaft 28 journaled also in the bed 10. Intermediate 75 their ends the arms 26 and 27 carry, respectively, pins 29 and 30 which project inwardly through the bed 10. To this end the bed adjacent each of the pins 29 and 30 is provided with an arcuate slot 31. The pins 29 and 30 are connected, respectively, to the rear face 32 of the bed 10 by coiled springs 80 33 and 34.

With this construction the springs 33 and 34 tend to hold the narrow marking face 18 85 engaged with an ink pad 35. The ink pad 35 is rectangular and is loosely received in a tray 36 formed on a horizontal portion of the bed 10 at a level above the pattern 4. By 90 engaging the handle 22 the operative may swing the narrow marking edge face 18 from a position where it engages the ink pad 35 to a position where it marks the vamp 3, as shown by comparison of the full and construction lines in Fig. 2. After the marking 95 operation the springs 33 and 34 return the narrow edge face 18 to the ink pad aided, it may be, by the operative through manipulation 100 of the handle 22.

In order to prevent the narrow edge face 110 18 from cutting into the surface of the ink pad 35 and thus forming a groove therein into which ink may collect for transfer to the sides of the flange 19, the ink pad 35 is provided with a smooth surface formed by the 115 thick skin or tegument on a sheet of sponge rubber is vulcanized in a mold under heat and pressure so that the rubber surfaces adjacent the faces of the mold are consolidated to form a thick tegument extending 120 about the interior cells of the sponge rubber. The consolidated tegument presents a smooth elastic surface to the sharp marking edge 18 and resists the sinking of the sharp marking edge 18 deeply into the ink 125 pad. The tegument is elastic so that the smooth surface thereof is restored intact immediately upon the removal of the sharp marking edge 18 therefrom. The elasticity 130 of the tegument prevents ink from being de-

posed upon any other portion of the flange 19 than the narrow marking edge face 18 thereof.

The tegument is, however, impervious to 5 the ink supplied thereto and consequently the ink pad is limited as a source of supply to the amount of ink with which the surface of the tegument may be coated.

In order that the tegument of the ink pad 10 35 may be supplied with a coat of ink each time the marking edge 18 is transferred from the ink pad 35 to the vamp 3, the rear edge of the tray 36 is embraced by a flange 37 on a shallow pan 38 forming a source of ink 15 supply. The pan 38 holds a rectangular sheet or pad of sponge rubber 30, the tegument of which has been removed to render it pervious to ink. The pan 38 is secured by screws 40 to a block 41 provided with a 20 flange 42 which embraces the bottom of the vertical rear face 32 of the bed 10.

In order to transfer ink from the source of ink supply to the tegument of the ink pad 35 the sponge rubber sheet 39 is engaged by 25 a sponge rubber roll 43, the tegument of which has been removed to render it pervious to ink. The roll 43 is supported by a shaft 44 provided with reduced portions 45 and 46 formed, respectively, near the opposite ends thereof. The reduced portion 45 is embraced by the hooked end of an arm 47 which is loosely mounted upon a cotter-pin 48 carried by the arms of a yoke 49 on the cross-head 21. The reduced portion 46 of 30 the shaft 44 is embraced by the hooked end of an arm 50 which is loosely mounted on a cotter-pin 51 carried by the arms of a yoke 52 on the cross-head 21. The roll 43 is pressed into engagement with the sponge rubber 35 sheet 39 by springs 53 and 54. The spring 53 is coiled about the cotter-pin 48. The opposite ends of the spring 53 are hooked, respectively, over the arm 47 and one of the arms of the yoke 49. The spring 54 is coiled 40 about the cotter-pin 51 with its opposite ends hooked, respectively, over the arm 50 and one of the arms of the yoke 52.

With this construction the roll 43 is pressed yieldingly into engagement with the 50 sponge rubber sheet 39. When the handle 22 is grasped by the operative and the marking face 18 is swung from a position where it engages the ink pad 35 to a position where it engages the vamp 3 the roll 43 is rolled over 55 the sheet 39, the flange 37 and the ink pad 35. During its engagement with the sheet 39 the roll 43 absorbs ink therefrom which, as the roll 43 rolls over the ink pad 35, is deposited thereon in the form of a thin film 60 or coat. When the marking face 18 is returned to the ink pad 35 the roll 43 is returned into engagement with the sheet 39.

As shown in Fig. 2 the marking pattern swings through an arc in moving from its 65 high level position in engagement with the

ink pad 35 to its low level position in engagement with the vamp 3. During this and the return movement of the marking pattern, the axis of the roll 44 travels in a horizontal plane notwithstanding the fact that the actuating member for the roll 44 is the swinging cross-head 21. This straight line movement of the roll 43 is permitted by the springs 53 and 54 which hold the roll 43 in engagement with the sheet 39 or the ink pad 35 independent of the position the cross-head 21 assumes during its swinging movement.

The roll 43 may be removed readily from the device by freeing the shaft 44 from the hooked ends of the arms 47 and 50. The sheet 39 may be removed from the pan 38. Owing to the porous nature of the sheet 39 it contains most of the ink in the pan. By removing the roll 43, the sheet 39, by wiping the shallow pan 38 and the tegument of the ink pad 35, and by substituting another roll 43 and another sheet 39 for the removed roll and sheet, the device may be quickly changed to mark upper blanks with an ink of a different color.

As explained in my patent hereinbefore referred to, the marking pattern and the work supporting and guiding gage 4 are correlated to mark a line, for use as a guide in a subsequent operation, on a predetermined portion of the work. To this end the center lines of the pattern, gage and the work are arranged in the same vertical plane. The portion of the work upon which the guide line is to be marked is predetermined by the shoe designer who cuts out a pattern showing the shape of the upper blank. Cut through this pattern is a slot or an opening, the walls of which represent the configuration and location of the guide line desired. This guide line is reproduced on the marking face 18 of the flange 19. A blank gage 4 is placed in position over the dowels 11 on the plate 8 and the marking face 18 bearing the proposed design is inked by engagement 105 with the ink pad 35 and then swung into engagement with the blank gage 4 to mark it with the proposed design. The pattern from the shoe designer is then placed on the gage 4 and the slot or opening in the pattern brought into registry with the proposed design marked on the gage. By means of a pencil a line is drawn on the gage 4 using one edge of the pattern as a guide. Then 110 the isolated blocks 6 of the guide wall are inserted through the gage 4 so that the line drawn thereon is tangential to each of said blocks. With this construction and mode of operation the marking pattern and the work supporting gage are correlated so that whenever they are assembled together in the marking device their center lines and the center line on the work supported on the gage 4 will be in the same vertical plane.

While the marking device of the present invention is designed primarily to mark a line to indicate the lap of one upper blank over an adjacent blank or the location of an overlay on the blank, it will be apparent that the marking pattern may be shaped to mark a line to indicate the location of stitches having utilitarian or ornamental functions.

What is claimed as new, is:

- 10 1. In a marking device, the combination with means for supporting the work, and a marking member having a narrow edge face for depositing a marking substance on the supported work, of means for supplying the edge face with the marking substance comprising a sponge rubber pad having a consolidated tegument directly engageable with the edge face.
- 15 2. In a marking device, the combination with means for supporting the work, a stationary ink pad, and a marking member movable from a position where it engages the ink pad to a position where it marks the work, of means independent of the work supporting the ink pad with ink during each cycle of operations of the marking member.
- 20 3. In a marking device, the combination with means for supporting the work, an ink pad composed of sponge rubber having a consolidated tegument, and a marking member movable from a position where it engages the tegument to a position where it marks the work, of means for supplying the tegument with ink during each cycle of operations of the marking member.
- 25 4. In a marking device, the combination with means for supporting the work, an ink pad composed of sponge rubber having a consolidated tegument, and a marking member movable from a position where it engages the ink pad to a position where it marks the work, of a roll composed of sponge rubber having its tegument removed to render it pervious to ink for supplying the ink pad with ink during each cycle of operations of the marking member.
- 30 5. A marking device having, in combination, stationary means for supporting the material to be marked, a stationary source of marking substance supply, a stationary marking substance pad, means for making impressions on the material to indicate the outline of a subsequent operation, means for moving the marking means from a position where it receives the marking substance from the pad to a position where it presses upon the material to be marked and makes an impression thereon with the marking substance to indicate the outline of a subsequent operation, and movable means for transferring marking substance from the source of supply to the pad.
- 35 6. A marking device having, in combination, stationary means for supporting the work to be marked, a stationary source of marking substance supply, a stationary marking substance pad, means for making impressions on the work to be marked to indicate the outline of a subsequent operation, means for moving the marking means from a position where it receives the marking substance from the pad to a position where it presses upon the work to be marked and makes an impression thereon with the marking substance to indicate the outline of a subsequent operation, and movable means for transferring marking substance from the source of supply to the pad.
- 40 7. A marking device having, in combination, a base member provided with two horizontal stationary surfaces on different levels, the lowest level supporting the material to be marked, and the highest level supporting a marking substance pad, a source of marking substance supply adjacent the highest level, means for making impressions on the material to be marked to indicate the outline of a subsequent operation, a swinging member hinged to the base member upon which the marking means is mounted for movement from a position where it rests upon the pad to a position where it presses upon the material to be marked and makes an impression thereon with the marking substance to indicate the outline of a subsequent operation, and means connected to the swinging member for transferring marking substance from the supply to the pad.
- 45 8. A marking device having, in combination, means for supporting the work to be marked, a source of ink supply, a sponge rubber pad having a consolidated tegument impervious to ink, means for making impressions on the work to be marked to indicate the outline of a subsequent operation, means for moving the marking means from a position where it engages the ink pad to a position where it presses upon the work to be marked and makes an impression thereon with the marking substance to indicate the outline of a subsequent operation, a sponge rubber roll having its tegument removed to render the roll pervious to ink, and means for rolling the roll out of the supply and over the pad when the marking means is moved from the ink pad to mark the work.
- 50 9. In a marking device, the combination with a work supporting gage, a stationary ink pad, a marking pattern, a swinging head therefor movable to transfer the marking pattern from a position where it engages the ink pad to a position where it engages the work, and a stationary source of ink supply, of means connected to the head for transferring ink from the source of supply to the ink pad.
- 55 10. In a marking device, the combination with a work supporting gage, an ink pad, a marking pattern, a swinging head therefor

material to be marked, a stationary source of marking substance supply, a stationary marking substance pad, means for making impressions on the material to indicate the outline of a subsequent operation, means for moving the marking means from a position where it receives the marking substance from the pad to a position where it presses upon the material to be marked and makes an impression thereon with the marking substance to indicate the outline of a subsequent operation, and means movable with the marking means for transferring marking substance from the source of supply to the pad.

70 75 80 85 90 95 100 105 110 115 120 125

8. A marking device having, in combination, means for supporting the work to be marked, a source of ink supply, a sponge rubber pad having a consolidated tegument impervious to ink, means for making impressions on the work to be marked to indicate the outline of a subsequent operation, means for moving the marking means from a position where it engages the ink pad to a position where it presses upon the work to be marked and makes an impression thereon with the marking substance to indicate the outline of a subsequent operation, a sponge rubber roll having its tegument removed to render the roll pervious to ink, and means for rolling the roll out of the supply and over the pad when the marking means is moved from the ink pad to mark the work.

9. In a marking device, the combination with a work supporting gage, a stationary ink pad, a marking pattern, a swinging head therefor movable to transfer the marking pattern from a position where it engages the ink pad to a position where it engages the work, and a stationary source of ink supply, of means connected to the head for transferring ink from the source of supply to the ink pad.

10. In a marking device, the combination with a work supporting gage, an ink pad, a marking pattern, a swinging head therefor

movable to transfer the marking pattern from a position where it engages the ink pad to a position where it engages the work, and a source of ink supply, of a pressure roll for transferring ink from the source of supply to the ink pad.

5 11. In a marking device, the combination with a work supporting gage, an ink pad elevated above said gage, a marking pattern, a swinging head therefor movable to transfer the marking pattern from a position where it engages the ink pad to a position where it engages the work, a source of ink supply including an ink pad arranged in the same 10 horizontal plane as the first named ink pad, and a roll for transferring ink from the pad in the source of supply to the other ink pad, of means connecting the head and the roll permitting the axis of the roll to move in a 15 single plane while the head swings through 20 an arc.

12. In a marking device, the combination with a work supporting gage, an impervious ink pad, a marking pattern movable from a 25 position where it engages the impervious pad to a position where it marks the work, and a pervious ink pad, of a pervious roll for transferring ink from the pervious to the impervious ink pad.

30 13. In a marking device, the combination with a work supporting and guiding pattern, a stationary ink pad immune from sulcation, a marking member having a sharp marking edge face, and a swinging head for moving 35 the marking pattern from a position where the sharp edge face engages the ink pad to a position where it engages the work, of means connected to the head for wiping ink over the surface of the ink pad engaged by 40 the sharp edge face.

14. In a marking device, the combination with a work supporting gage, an ink pad elevated above said gage, a marking pattern, a swinging head therefor movable to transfer 45 the marking pattern from a position where it engages the ink pad to a position where it engages the work, a source of ink supply including an ink pad, and a roll for transferring ink from the pad in the source of supply 50 to the other ink pad, of arms loosely mounted on the swinging head for supporting the rolls at the opposite ends thereof, and a spring interposed between the head and each arm for pressing the roll downwardly.

55 In testimony whereof I have signed my name to this specification.

HERBERT E. EDWARDS.

CERTIFICATE OF CORRECTION.

Patent No. 1,796,686.

Granted March 17, 1931, to

HERBERT E. EDWARDS.

It is hereby certified that error appears in the printed specification of the above numbered patent requiring correction as follows: Page 1, line 71, for the word "for" read of; page 2, line 43, for "gate" read gage, and line 117, after the word "rubber" insert a period and the words The sheet of sponge rubber; and that the said Letters Patent should be read with these corrections therein that the same may conform to the record of the case in the Patent Office.

Signed and sealed this 14th day of April, A. D. 1931.

M. J. Moore,
Acting Commissioner of Patents.
